UNITED STATES PATENT OFFICE.

CARL HEINZEN, OF CHICAGO, ILLINOIS.

BAG FILLING AND TYING MACHINE.

1,084,799.

Specification of Letters Patent. Patented Jan. 20, 1914.

Application filed September 7, 1905. Serial No. 277,345.

To all whom it may concern:

Be it known that I, CARL HEINZEN, a citizen of the United States, and a resident of Chicago, county of Cook, and State of Illinois, have invented certain new and useful Improvements in Bag Filling and Tying Machines, of which the following is declared to be a full, clear, and exact description.

The improvement relates to bagging machines and more particularly to the mechanism for automatically tying up the mouths of the bags as the latter are filled.

The invention seeks to provide reliable and effective mechanism whereby the bags may be rapidly filled and tied and the invention consists in the features of construction, combinations and arrangements of parts hereinafter set forth, illustrated in the accompanying drawings and more particularly pointed out in the appended claims.

In the drawings, Figure 1 is a plan view of the machine. Fig. 2 is a side elevation thereof. Fig. 3 is a detail view of one of the grips or catches for holding the mouth of the bag. Figs. 4 and 5 are sectional views taken on the lines 4—4 and 5—5 respectively of Fig. 1. Fig. 6 is a front view of the slotted cord-guide. Fig. 7 is an enlarged detail view of part of the operating mechanism shown in Fig. 5. Fig. 8 is a horizontal section on line 8—8 of Fig. 4. Fig. 9 is a similar view with the neck-forming jaws shown in closed position and with parts of the operating mechanism omitted for the sake of clearness. Fig. 10 is an enlarged detail section on line 10—10 of Fig. 11. Fig. 11 is an enlarged detail plan view of the cord mechanism in the position assumed after it has passed the cord around the neck of the bag. Fig. 11^a is a detail section on line a—a of Fig. 11. Fig. 12 is a side elevation thereof with certain parts shown in section. Fig. 13 is a detail section on line 13—13 of Fig. 11. Fig. 14 is a detail section on line 14—14 of Fig. 12. Fig. 15 is a sectional view of the wire twisting device and its operating mechanism. Fig. 16 is an elevation thereof with the slotted guide plate omitted. Fig. 17 is an elevation of the inner face of the slotted cord guide. Figs. 18, 19 and 20 are views illustrating the operation of the wire twisting device.

The frame of the machine comprises the side pieces 1 which are preferably formed of cast metal and provided with legs 2. The latter are shown broken away but are of sufficient length to hold the machine at the desired height. The side pieces 1 are connected at their upper ends by the cross angle bars 3 and by the cast member 4, which is provided with a central depending portion or mid-rib 5 shown in Figs. 2, 4 and 5. The main drive shaft 6 is journaled in the sides of the frame and carries a drive pulley 7 on its outer end. A supplemental drive shaft 8 is journaled between the sides of the machine and is connected by gears 9 to the main drive shaft 6.

A pair of guide rails 10 are mounted upon the top cross pieces 3. These guide rails are preferably formed of angle bars, as shown, having upwardly extending flanges and they project beyond the front end of the machine. A ring-like carrier frame 11 is arranged to reciprocate on the forward ends of the guide rails 10, and, for this purpose, is provided with grooved rollers 12 that engage the upwardly extending flanges of the guide rails. The reciprocating carrier supports a hopper 13 through which the grain or other material is directed into the bag. The carrier is also provided with a series of catches for engaging the mouth of the bag and holding it open beneath the lower end of the hopper. These catches are preferably mounted upon a number of arms 14 that are pivoted in a circular series between pairs of radially disposed lugs or ribs 15 on the reciprocating carrier 11. These arms depend below the carrier and are provided on their lower ends with the bag-engaging catches. The upper end of the arms above their pivots are provided with anti-friction rollers 16, arranged within the cam slots 17 of a flat ring shaped cam 18. This cam ring is journaled upon the upper end of the central cylindrical portion of the carrier frame 11 (see Figs. 4 and 5) and rests, as shown, on the flange 11^a above the radially projecting ribs or lugs 15. The cam is held against vertical movement by a ring or washer 19 fitted about and secured to the inner end of the central cylindrical portion of the carrier frame.

The carrier frame is oscillated upon the

guide rails 10 by a shifter-rod or lever 20 that is loosely journaled at its lower end upon the main drive shaft 6 and extends upwardly therefrom, and which carries a pin or roller 21 engaging the slot of a cam 22 on the counter-shaft 8 (see Figs. 5 and 8). A pair of links 23 is pivoted to the upper end of the lever and to a radial rib or abutment 24 on the carrier.

- 10 The catches 25 for holding the mouth of the bag are preferably hook-shaped (see Figs. 2 and 3) and pivoted between pairs of plates 26 that are secured to the lower ends of the arms 14. Each hook-like catch preferably extends upwardly and inwardly from its pivot and its free end is held by a leaf-spring 27 into engagement with an abutment 28 secured between the plates 26. The lower ends of plates 26 are cut away so that the 20 edge of the mouth of the bag may be quickly and easily slipped into place between the hooks 25 and the abutments 28 when the catches are in their outward position. Each catch is provided with an upwardly extending lug 29 which is arranged to be engaged by a trip-dog 30 that is pivoted between the plates 26 and has an inwardly projecting tail-portion 31.

The movement of the cam ring is controlled preferably by a link 32 (see Fig. 1) that is connected at one end to one side of the main frame by a pivot bolt 33 and at its other end to a slotted lug 34 on the ring frame by a pivot bolt 35. The connecting 35 link is preferably made adjustable for varying the throw of the cam-ring and such adjustment is preferably effected by forming the link of separate sections having the right and left hand screw threads and connected 40 by a turn-buckle 36.

It will be noted as shown in Fig. 1, that a part of each of the cam slots 17 of the ring 18, extends in circumferential direction while a part of each slot is inclined. As the carrier frame is moved inwardly toward the main frame of the machine, the cam-ring, as it moves inwardly with the carrier, will be so turned as to bring the rollers on the upper ends of the arms 14 within the circumferentially extending portions of the cam slots. In this position, the catches on the lower ends of the arms will be held together, as shown in Fig. 4. When the carrier frame moves outwardly the cam-ring 55 will be so turned as to bring the upper ends of the arms within the inclined portions of the cam slots and the catches will be moved outwardly or apart, as indicated in Figs. 1 and 2. In this position, the bag may be 60 placed on the catches and it is then filled by admitting grain or other material through the hopper 13.

The extent to which the catches are moved outwardly may be varied by adjusting the 65 length of the controlling link 32 so that the

machine may be used with bags of different sizes.

As soon as the bag is filled, the carrier is moved toward the main frame and the catches on the lower ends of the arms 14 are moved inwardly to close the mouth of the bag as indicated in Fig. 6, and in this innermost position of the carrier frame and catches, the upper portion of the bag is brought into the path of the neck-forming and bag-tying mechanism. As shown in Fig. 5, the slot of cam 22 is so shaped that the carrier frame will be held stationary in its outermost position for a considerable part of the revolution of the counter-shaft 8 during which time the bag is placed in position upon the catches and filled. The bag will then be quickly drawn in and held in its innermost position during the operation of the neck-forming and bag-tying mechanisms. 75 The carrier frames will then be moved outwardly to receive a new bag. A spring 37 extends between the upper end of the shifter-rod 20 and the rear cross bar 3 of the main frame so as to take up lost motion of the pin 90 or roller 21 within the slot of cam 22, thus 80 steady the motion of the carrier and securely holding it in its outer and inner positions during the bag-filling and bag-tying operations respectively. 95

At the end of the bag-tying operation, the catches 25, which hold the bag, are preferably automatically released by a suitable mechanism. In the form shown, this mechanism comprises a plunger 38 of inverted frustum-cone shape that is pivoted upon the lower end of a link 39. The latter is pivoted to the end of an arm 40 upon a rock-shaft 41 that extends across the front of the machine at its upper end and is journaled at its ends 100 in brackets 42. A rock-arm 43, on the end of the rock-shaft 41 (see Fig. 2), is connected by a link 44 to a rocking lever 45 pivoted on the side of the frame. A spring 46 extending between the end of the arm or 110 lever 45 and an upright bolt 47 on the frame, holds a pin or roller 48 on the arm into engagement with a cam 49 on the end of the counter-shaft 8. The bolt 50 that connects the link 44 with the arm 43, preferably extends through a slot 51 so that the extent of the throw of the tripping plunger may be 115 adjusted as is necessary. Link 39 abuts against a shoulder 52 on the rock-arm 40 so that it is normally held centrally over the inner position of the bag-holding catches. As the plunger 38 is shifted downwardly, it engages the tail portions 31 of the trip dogs 30 and shifts the catches 25 outwardly 120 against the tension of the springs 27 so as to release the bag. The inner ends of the tail portions 31 of the trip dogs 30 are inclined downwardly and inwardly as shown, in correspondence with the conical shape of the plunger 38, so that the plunger, which is 13

freely suspended on the link 39, will accurately center itself as it is shifted downwardly and will trip all of the catches to release the bag.

In the innermost position of the carrier, the upper portion of the bag, as indicated in Fig. 4, is held against or closely adjacent a guide bar 53 that is preferably curved and preferably forms a horizontal flange on the lower edge of a curved frame member 54 (see Figs. 2, 4, 5 and 8). The neck-forming devices for gathering the folds at the mouth of the bag are preferably in the form of a pair of jaws 55 that are mounted on the outer ends of arms 56. These arms both extend through an opening 57 in the mid-section or rib 5 of the main frame, and are journaled at this point on an upright pivot bolt 58. A pair of links 59 are pivotally connected at their forward ends to the ends of the arms 56 and are connected at their rear ends by a common pivot bolt 60 to a U-shaped piece 61, as most clearly shown in Fig. 4. The latter is connected by a pair of links 62 (see Figs. 4 and 9) to the upper end of a shifter-rod 63. The latter is loosely journaled at its lower end on the shaft 6 and carries a pin or roller 64 which engages the slot of a cam 65 on the drive shaft 8.

The outer ends of the arms 56 extend beneath the guide-bar 53, and are provided with clips 66 that extend over the guide-bar so that the weight of the neck-closing jaws is supported at this point. The mechanism described is arranged to expand and contract the operating arms 56 and neck-forming jaws 55. The latter are provided with fingers 67, the ends of which are just below the outer edge of the guide-bar 53. The jaws are also provided with forwardly and inwardly extended portions 68 which engage the upper portion of the bag as the jaws are moved inwardly. In this latter position the neck-forming jaws overlap, as shown in Fig. 9, leaving only a round opening between the fingers 67 and projecting portions 68 through which the neck of the bag extends.

The cam 65 is so shaped (see Fig. 4) that the jaws are held in stationary open position as the bag is being filled. When the upper portion of the bag is moved inwardly the jaws are quickly closed and are shaped, as described, to gather the folds at the upper portion of the bag into a neck so that the mouth of the bag is held securely closed. The jaws are held in this position during the bag-tying operation.

Beneath the center of the guide-bar 53 and in rear of the position in which the neck of the bag is held by the jaws 55, is arranged a block 69 that is preferably formed of separate upper and lower sections bolted together, the upper section of the block be-

ing secured to or cast in piece with the guide-bar 53. To the front and at one end of this block is secured a guide plate 70 (see Fig. 6) that is provided with a horizontal guide slot 71 having a flared open end. The sections of the guide block 69 are shaped to form a corresponding guide slot, as indicated in Fig. 5.

In rear of the block 69 is arranged the duplex cord clamp and cutter that is carried upon a short, vertical spindle or shaft 72 journaled in lugs 73 projecting from the rear face of the curved frame member 54 (see Figs. 5, 8, 11, 12 and 14). A spur pinion 74, fixed to the spindle between the lugs 73, meshes with a spur gear 75 loosely journaled upon the upper end of a short shaft 76. The latter is journaled in a suitable bearing in the forward end of the mid-section or rib 5 of the main frame. An arm 77 (see Figs. 4 and 12) fixed to the lower end of the vertical shaft 76 has a bolt and slot connection with the forward end of a shifter-rod 78 (see dotted lines in Fig. 9) that is guided in suitable bearing lugs 79 on the lower edge of the mid-rib 5. A spring 80 coiled around the rod extends between the rear lug 79 and a collar 81 on the end of the rod, and normally holds it in retracted position.

A finger 82 on the counter-shaft 8, is arranged to engage a slot 83 in the shifter-rod to project it forwardly, once for every operation of the machine, a sufficient extent to rotate the shaft 76 through a quarter turn. As soon as the finger 82 passes out of the slot 83, spring 80 returns the shifter-rod to its normal position. An arm 84 on the upper end of the shaft 76 (see Figs. 8 and 12) carries a spring-held pawl 85 which is arranged to engage a ratchet wheel 86 that is secured to the gear 75. Ratchet wheel 86 has four teeth so that at the proper time in each operation of the machine, shaft 76 is given a quarter turn and spindle 72 is given a half turn since the gear 75 has twice as many teeth as the pinion 74.

The duplex cord clamp and cutter is clearly shown in Figs. 11, 12 and 14 and comprise upper and lower members 87 and 88. The lower member 87 is fixed centrally upon the lower end of the rotatable spindle 72, as clearly shown in Figs. 11 and 14. The upper member 88 of the clamp is of inverted U-shape as indicated in Fig. 12 and sets over the lower member 87 and is centrally pivoted thereto by the pivot screws 89, and the members are so shaped that when in engagement at one end their opposite ends will be separated as shown in Fig. 14. A stationary cam 88a is fixed upon the under face of the lower lug 73 and extends about the rotating spindle 72. This cam engages the upper face of the oscillating clamp member 88 and holds it in the position shown in

Fig. 14 with one end of the upper oscillating clamp member 88 in engagement with one end of the lower clamp member 87, while the opposite ends of these clamp members are open, as shown. The opposite ends of the two clamp members thus form, in effect, two pairs of jaws, one of which is normally closed and the other of which is normally open. When the spindle 72 is given a half revolution as described, the upper and lower members 87 and 88 of the duplex clamp are also rotated a half revolution and the fixed or stationary cam 88^a will shift the upper oscillating clamp member 88 to separate the engaged ends of the clamp members and bring together the opposite ends thereof. That is to say, at each half revolution of the spindle 72, which occurs at each operation of the machine, the closed pair of jaws of the clamp members is opened and the opened pair of jaws is closed. The upper oscillating clamp member 88 is provided at each side and near its opposite ends with downwardly extending cutting knives 90 which coöperate with upwardly extending cutting knives 91 on a plate 92 that is fixed to the rotating spindle 72 below the lower clamp member 87. The knives 90 and 91 at the closed ends of the clamp members are in engagement, as shown in Fig. 12, while the knives at the opposite or opened ends of the clamp members are separated, as shown in Fig. 14.

A shifter-arm 93 (see Figs. 8, 9 and 11) is arranged below the guide 53 and is connected thereto at a point to one side of the center, by a pivot bolt 94. An operating arm 95 is connected by a pivot pin 96 to a lug on the mid-rib of the main frame and is connected to the shifter-arm by a link 97. A bolt 98, fixed to one of the jaw-operating arms 56, extends through a slot 99 in the arm 95 so that the shifter-arm 93 is actuated, as the neck-forming jaws shift to closed position, to carry the cord around the neck of the bag, as shown in Figs. 9 and 11. The cord shifter arm 93, the end of the operating arm 95 and the connecting link 97 are bent, as shown, so that the cord may be properly carried around the neck of the bag.

The cord shifter arm is provided on its end with a pivoted dog 100 (see Fig. 11), that is held by a spring 101 against the shoulder 102 on the arm. The free end of the cord is held between the closed pair of jaws of the duplex cord clamp and extends thence outwardly through the slotted cord guide and then through an eyelet in the end of the dog 100, and thence through a series of guides 103 on the shifter-arm. The open position of the neck-forming jaws and cord shifter is shown in Fig. 8. As the jaws are brought together into the position shown in Fig. 9, the shifter-arm operates to carry the cord around the neck of the bag and again

through the slotted cord guide 70 and through the open pair of jaws of the duplex cord clamp and cutter (see Figs. 11, 12 and 14). The ends of the cord about the neck of the bag are then secured together, as hereinafter described, and the duplex cord clamp is then given a half revolution by its operating mechanism, so that its open pair of jaws is closed and the cutting knives 90 and 91 thereon operate to sever the length of cord secured about the neck of the bag, and the new free end of the cord is gripped. At the same time, the closed pair of jaws are opened to release the length of cord around the neck of the bag and are moved around into position to receive the cord at the next operation. The return movement of the neck-forming jaws and cord shifter carries the cord back out through the slotted cord guide and into position shown in Fig. 8 in readiness to tie up the next bag.

A suitable device is preferably employed for tightening the cord after it has been passed around the neck of the bag by the shifter-arm. This tightening device comprises a pair of jaws 105 (see Figs. 5, 11, 12 and 13) which are mounted upon a block 106 arranged to slide in a slot or guide-way 107 in the lower portion of the mid-rib 5. The side of this slot is open and is closed by a plate 108. An operating spring 109 is arranged within the guide-way 107 and is connected at its ends to the block 106 and to the frame of the machine. Block 106 is provided with a bar 110 arranged to slide behind the plate 108, and having a laterally projecting pin 111 at its rear end which is arranged to be engaged by a finger 112 on the counter-shaft 8 (see Fig. 4). The engagement of the finger or rod 112 with the pin 111, shifts the cord-tightening device forwardly and the latter is held in such forward position by a spring catch 113 (see Figs. 10 and 11) that is arranged transversely within the forward end of the guide-way 107 and is adapted to engage a lug 114 on the cord-tightening device to hold it in its forward position.

The outer ends of the jaws 105 extend through a slot 115 in the plate 108, and this slot, as clearly shown in Fig. 5, has an enlarged portion at its outer end. The inner ends of the jaws extend within a slot 116 in the side of the guide-way 107, and this slot is provided with a contracted portion at its outer end (see Fig. 11^a), so that the projecting or outer ends of the said jaws are held open when the cord-tightening device is in its forward position in engagement with the latch 113.

The outermost position of the jaws 105 of the cord-tightening device is indicated in dotted lines in Figs. 9 and 11. In this position the cord will extend through the open jaws when it is passed around the neck

of the bag by the shifter-arm. A lug 117 on the shifter-arm 93 at the end of its movement, strikes against a projection 118 on the spring latch 113, (see Fig. 11) and releases it so that the cord-tightening device is drawn rearwardly by its operating spring. As the outer ends of the jaws are drawn rearwardly into the contracted portion of the slot 115, the jaws are closed, grip the 10 cord and draw it tightly around the neck of the bag. The spring-held dog 100 on the end of the shifter-arm yields to permit this rearward movement of the cord-tightening jaws. After the shifter-arm has returned 15 to its initial position the cord-tightening device is again shifted to its forward position into engagement with the latch 113, and as the inner ends of the jaws pass into the contracted portion of the slot 116, the outer 20 projecting ends are again opened to receive the cord at the next operation of the machine.

The ends of the length of cord around the neck of the bag are secured together 25 by winding a length of wire around them. This wire winding or twisting device is arranged within the sectional block 69 in rear of the slotted guide plate 70 (see Fig. 12 and Figs. 15 to 20 inclusive), and comprises inner and outer rotatable members 119 and 120. The outer member 120 is provided with a socket within which the inner member 119 fits and both members are provided with radial slots that extend to the 30 centers of the rotatable members and that are normally held in line with the slots of the block 69 and guide plate 70. The inner member 119 of the wire twisting device is positively driven and for this purpose is 35 provided on its inner end with gear teeth 121 that mesh with the teeth of an idler 122 on a short shaft 123 mounted between the sections of the block 69. The outer end of a horizontal shaft 124 extends between the 40 sections of the block 69 and is provided with a gear 125 meshing with the teeth of the idler 122. This shaft is journaled in suitable bearings 126 on the lower end of the mid-rib of the main frame (see Figs. 4, 5 and 8) and at its rear end is provided with a beveled gear 127 meshing with a beveled gear 128 on a cross shaft 129. The latter shaft is mounted in suitable bearings 130 (see Fig. 8) on the mid-rib of the frame 45 and on one of the sides of the frame, and carries a pinion 131 that meshes with the teeth of the gear 132 on a cross shaft 133 journaled in suitable bearings 134 in the sides of the main frame. The shaft 133 50 (see Figs. 7 and 8) is provided with a small gear 135 that is arranged to be intermittently engaged by the teeth of a mutilated gear 136 on the driving or counter-shaft 8, so that at proper intervals shaft 124 is rotated to operate the wire twisting device. 55

This drive gearing is such that the wire twister is given exactly two revolutions at each operation of the machine.

In order that the slots of the wire twister, when in idle position, shall be accurately held in line with the slots of the cord guide plate 70 and in proper position to receive the ends of the cord, its drive mechanism is provided with a Geneva stop movement. For this purpose the mutilated gear is provided with a cylindrical locking surface 137, (see Fig. 7) which co-operates with a locking wheel 138 on the shaft 133, and this locking surface is provided with a cut-away portion 139 opposite the teeth of the mutilated gear so as to permit the passage of the raised portions of the locking wheel 138. By the mechanism described, the wire twister will at proper time, be given two revolutions. At all other times it will be locked against movement and held with its slots in line with the slots of the cord guide. The inner rotatable member 119 of the wire twister is thus positively driven by the gearing described, and is provided at its end with an eccentric finger 140 (see Figs. 15 and 16) that extends through a slot 141 in the end of the outer member 120, so that the outer member is driven by the engagement of this finger with the end of the slot, but the slot is somewhat larger than the finger so that there is a lost motion connection between the members of the wire twisting device. The fingers 140 and the end of the slot 141 also serves as a grip for the length of wire to be twisted around the ends of the cord. The outer member is provided with a groove 142, the bottom of which is raised at one portion to form an abutment 143. The surface of this abutment is even with the cylindrical surface of the cylindrical member 120 and is provided with a depression 144 (see Figs. 19 and 20) that is arranged to be engaged by the end of a spring-held plunger 145, extending upwardly through the lower section of the block 69. By this means the outer loose member of the wire twisting device is held in its idle position with its slot in proper position to receive the ends of the cord. In this position too, the grip fingers 140 in the forward edge of the slot 141, are held apart to receive the end of the fastening wire.

At the proper time, the wire is fed through a guide-way or slot 69* in the face of the upper section of the block 69 into the position shown in Fig. 18, with the end of the wire between the grip fingers 140 and the forward end of the slot 141. The outer side of the guide slot 141 is normally closed by the plate 70, which is removed for the sake of clearness in Figs. 16 to 20 inclusive.

The wire is fed intermittently at proper intervals in any suitable manner. A pair of feed rolls 146 and 147 (see Fig. 4) are pro- 139

vided for this purpose. Feed roll 147 is mounted on a bracket 148 and feed roll 146 is mounted upon a cross shaft 149 that is journaled in the brackets 42 at the upper front portion of the frame (see Figs. 1 and 2). Shaft 149 is intermittently driven at proper intervals by a pawl and ratchet mechanism 150 (see Fig. 1) that is operated by an eccentric pin 151 on the end of the drive shaft 8, and a connecting link 152.

The inner face of the slotted guide plate is provided with a segmental shaped lug 153 (see. Figs. 12 and 17). The outer end or face of the member 120 of the wire twisting device is slightly convex, as shown, and abuts against the segmental projection or lug 153 on the guide plate 70. One portion of the face of the member 120 is slightly cut away to form an edge 154, that in the idle position of the twisting device, is in line with the guide groove 69, and this edge assists in guiding the end of the wire into engagement with the grip finger 140. A portion of the face of the member 120 adjacent the edge 154, is slightly raised (see Fig. 11) and a cutting edge 155 is formed on the forward edge of the raised portion 156.

The normal or idle position of the wire twisting device is shown in Figs. 15, 16 and 18. After the cords have been passed around the neck of the bag and through the slotted members 119 and 120, the end of the wire is fed into the position shown in Fig. 18 with its end between the grip finger 140 and the forward end of the slot 141. The wire twisting device is then driven in the direction indicated by the arrows in Figs. 18, 19, and 20. As stated, the inner member 119 having the grip finger 140, is positively driven, but the initial movement of the outer member 120 is somewhat retarded by the engagement of the spring plunger 145 with the depression 144 therein, so that the end of the wire is first securely gripped between the finger 140 and the forward edge of the slot 141. Both members then rotate in unison and carry the wire around the ends of the cords. When the wire twisting device has nearly completed a revolution the cutting edge 155 is brought into engagement with the wire, as shown in Fig. 19, and a suitable length of wire is cut off. When the wire is cut off, it has been twisted once around the ends of the cords, as shown in Fig. 20. During the second revolution of the twister the unwound portion of the wire would simply be carried around between the member 120 and the plate 70 if it were not for the presence of the abutment or lug 153, which engages the wire and insures that a second twist will be given to it during the second revolution of the wire winding device. In this manner the ends of the cord are firmly secured together about the neck of the bag.

When thus secured the bag is automatically

released from the catches as previously described, and the parts automatically returned to initial position in readiness to receive and tie up the next bag.

It is obvious that the invention is not limited to the details of the various mechanisms set forth and that numerous changes may be made in the details of construction without departure from the essentials of the invention. It is further obvious that parts of the invention may be taken without its adoption in entirety.

Having described my invention what I claim as new and desire to secure by Letters Patent is:—

1. In bagging machines, the combination with a circular series of radially movable catches for holding the mouth of the bag as it is filled, actuating mechanism for simultaneously shifting said catches together to close the mouth of the bag and for shifting the same apart, and means for adjusting the throw of said actuating mechanism to thereby vary the distance apart to which said catches are moved in accordance with the size of the bag, substantially as described.

2. In bagging machines, the combination with a series of arms pivoted in circular series having catches for holding the mouth of the bag as it is filled and means for shifting said arms radially to move said catches apart to receive the bag and to bring said catches together to close the mouth of the bag, substantially as described.

3. In bagging machines, the combination with the bag-tying devices, of a series of catches arranged in circular series and adapted to hold the mouth of a single bag as it is filled and actuating means for radially shifting said catches to move the same apart to receive the bag and to bring said catches together to close the mouth of the bag, substantially as described.

4. In bagging machines, the combination with the neck-forming jaws and bag-tying devices, of a number of arms pivoted in circular series and having catches on their lower ends for holding the mouth of the bag as it is filled and means for actuating said arms to move said catches apart to receive the bag and to move said catches together to close the mouth of the bag and hold the same in position for the operation thereon of said neck-forming jaws and bag-tying devices.

5. In bagging machines, the combination with the neck-forming jaws and bag-tying mechanism, of a number of arms pivoted in circular series and having catches on their lower ends for holding the mouth of the bag as it is filled, means for actuating said arms to shift said catches apart to receive the bag and bring the same together to close the mouth of the bag, and means for disengaging said catches from the bag.

6. In bagging machines, the combination with the neck-forming jaws and tying mechanism, of a number of arms pivoted in circular series and having catches on their lower ends for holding the mouth of the bag and a rotatable ring having cam slots engaging and operating said arms to move said catches together and apart. 70
7. In bagging machines, the combination 10 with the bag tying devices, of an open frame, a circular series of catches on said frame for holding the mouth of the bag below the opening therein, said catches being radially shiftable together and apart, and 15 means for shifting said catches, substantially as described. 80
8. In bagging machines, the combination with the bag tying devices, of the hopper and ring frame, a series of catches mounted 20 on said ring frame for holding the mouth of the bag below said hopper and means for shifting said catches together and apart, substantially as described. 85
9. In bagging machines, the combination 25 with the bag-tying devices, of a shifting carrier having a feed hopper, a series of catches mounted on said carrier for holding the mouth of the bag and means for shifting said catches to close the mouth of the bag 30 as said carrier is moved toward said tying devices. 90
10. In bagging machines, the combination with the bag-tying devices, of a reciprocating carrier shifting to and from said bag-tying devices, a series of catches on said carrier for holding the mouth of the bag and actuating means for shifting said catches together and apart as the carrier is shifted. 95
11. In bagging machines, the combination 40 with the bag-tying devices, of a reciprocating carrier shifting to and from said bag-tying devices, a series of catches on said carrier for holding the mouth of the bag, actuating means on said carrier for shifting 45 said catches together and apart and means for adjusting the throw of said actuating means. 100
12. In bagging machines, the combination with the bag-tying devices, of a reciprocating carrier shifting to and from said bag-tying devices, a series of catches on said carrier for holding the mouth of the bag, a cam-ring rotatably mounted on said carrier for shifting said catches together and apart 55 and a controlling link connected to said cam-ring and to the main frame of the machine. 110
13. In bagging machines, the combination with the bag-tying devices, of a reciprocating carrier movable to and from said bag-tying devices, a series of arms pivoted on said carrier having catches for holding the mouth of the bag and actuating means for moving said arms to shift said catches together and apart as said carrier is shifted. 120
14. In bagging machines, the combination with the neck-forming jaws and cord tying mechanism, of a reciprocating carrier and means carried thereby for holding the mouth of the bag and closing it as the upper portion of the bag is shifted into the path of the neck-forming jaws. 75
15. In bagging machines, the combination with the neck-forming jaws and cord tying mechanism, of a reciprocating carrier movable to and from said neck-forming jaws, catches on said carrier arranged in circular series for holding the mouth of the bag and means for shifting said catches together and apart as said carrier is shifted. 80
16. In bagging machines, the combination with the neck-forming jaws and cord tying mechanism, of a reciprocating carrier, a series of arms pivoted on said carrier having catches at their lower ends for holding the mouth of the bag, a cam ring rotatably mounted on said carrier for shifting said arms to move said catches together and apart and an adjustable link connection between said cam-ring and the main frame of the machine. 85
17. In bagging machines, the combination with the neck forming jaws and tying mechanism, of a reciprocating carrier comprising an open frame movable to and from said jaws, a series of catches on said carrier for holding the mouth of the bag below the opening therein, and means for shifting said catches together and apart. 90
18. In bagging machines, the combination 100 with a hopper, of a circular series of radially shiftable catches each comprising a pair of gripping jaws, for holding the mouth of the bag below said hopper as it is filled therefrom, and means for shifting said catches apart to receive the bag and for shifting the same together to close the mouth of the bag, substantially as described. 105
19. In bagging machines, the combination with the bag-tying devices, of a frame having an opening therein, a circular series of radially shiftable catches on said frame for holding the mouth of the bag below said opening as it is filled therefrom, mechanism for shifting said catches apart and for 110 shifting the same together to close the mouth of the bag, and means for disengaging said catches from the mouth of the bag when the latter are in position to close the mouth of the bag, substantially as described. 120
20. In bagging machines, the combination with the bag-tying mechanism, of a circular series of catches for holding the mouth of a single bag and radially shiftable together and apart and a movable plunger for releasing all of said catches, substantially as described. 125
21. In bagging machines, the combination with the bag tying mechanism, of an open frame, a circular series of catches on said 130 frame, a circular series of catches on said

frame for holding the mouth of the bag below the opening therein, means for causing said catches to converge to close the mouth of the bag, and means for releasing all of 5 said catches when shifted together.

22. In bagging machines, the combination with the bag-tying mechanism, of a number of catches arranged in circular series for holding the mouth of the bag, means for 10 moving said catches together and apart, a rock shaft having a crank arm thereon, a link pivoted to said crank arm and a plunger pivoted on the lower end of said link arranged to engage and release said catches 15 when shifted together.

23. In bagging machines, the combination with the bag-tying devices, of a reciprocating carrier movable to and from said bag-tying devices, a number of catches arranged 20 in circular series on said carrier, means for moving said catches together as said carrier shifts to said bag-tying devices and means for releasing said catches while held together.

24. In bagging machines, the combination with the bag-tying devices, of a carrier shiftable to and from said bag-tying devices, a series of arms pivoted on said carrier and having a series of catches on their lower 30 ends for holding the mouth of the bag, means engaging said arms for moving said catches together as said carrier is moved toward said bag-tying devices, a series of dogs on said arms engaging said catches and a 35 trip device for engaging said dogs and releasing said catches when the latter are together.

25. In bagging machines, the combination with the bag-tying devices, of a bag holder 40 comprising a number of pivoted catches arranged in circular series, said catches extending upwardly from their pivots, and a series of abutments with which the upper free ends of said catches engage to hold the 45 mouth of the bag.

26. In bagging machines, the combination of a bag-holder comprising a series of pivoted hook-shaped catches extending upwardly and inwardly from their pivots, a 50 series of abutments with which the upper free ends of the catches engage to hold the mouth of the bag and means for shifting said catches and abutments to close the mouth of the bag.

27. In bagging machines, the combination with the bag-tying mechanism, of a number of arms pivoted in circular series, hook-shaped catches pivoted on the lower ends of 55 said arms and extending upwardly and inwardly from their pivots, said arms having abutments with which the upper free ends of the catches engage to hold the mouth of the bag and means for shifting said arms to move the catches together and apart.

28. In bagging machines, the combination 65 with the neck-forming jaws and cord tying mechanism, of a carrier reciprocating to and from said neck-forming jaws, a series of arms pivoted on to said carrier, a series of catches and a series of trip dogs therefor 70 pivoted on the lower ends of said arms, means for actuating said arms as said carrier is shifted to move said catches together and apart and a shifting trip arranged to engage said dogs to release said catches when 75 the latter are in closed position.

29. In bagging machines, the combination with the bag-tying mechanism, of a pair of neck-forming jaws each having an outwardly inclined portion and an inwardly inclined finger and means for actuating the same, said inclined portions and said fingers being arranged to overlap in closed position to form the neck of the bag, substantially 80 as described.

30. In bagging machines, the combination with means for holding the mouth of the bag and the bag-tying devices, of a pair of neck-forming jaws each having an outwardly inclined portion and an inwardly inclined portion arranged to overlap in closed 90 position on opposite sides of the neck of the bag, said jaws being shaped to closely gather the upper portion of the bag into the neck about which the cord is passed, substantially 95 as described.

31. In bagging machines, the combination with the bag-tying devices, of a guide against which the bag is held, a pair of jaws each having an outwardly projecting inclined portion and a finger inwardly projecting toward said guide and operating means for the inclined portions and fingers of said jaws, said jaws being arranged to overlap in closed position to form the neck 100 of the bag, substantially as described.

32. In bagging machines, the combination with the bag-tying mechanism, of means for engaging and holding the mouth of the bag as it is filled, a pair of neck-forming jaws 110 operating below said bag-holding means, and means for opening and closing said jaws, each of said jaws having an outwardly inclined portion and an inwardly inclined portion, said inclined portions being arranged to overlap in closed position on opposite sides of the neck of the bag, substantially 115 as described.

33. In bagging machines, the combination with a hopper, of a series of catches for engaging and holding the mouth of the bag below said hopper as it is filled therefrom, a pair of neck-forming jaws movable below said catches, means for opening and closing said jaws, each of said jaws having outwardly and inwardly inclined portions, said portions being arranged to overlap in 120 closed position on opposite sides of the neck 125

of the bag, and means for securing a cord around the neck of the bag formed by the jaws, substantially as described.

34. In bagging machines, the combination 5 with the bag-holding and tying mechanism, of a pair of pivoted arms having jaws on their outer ends, a curved guide for the outer ends of said arms against which the upper portion of the bag is held and means 10 for spreading and contracting said arms and jaws, the latter being arranged to overlap in closed position to form the neck of the bag and accurately position the same with reference to the bag-tying devices.

35. In bagging machines, the combination 15 with the bag-holding and tying devices, a pair of neck-forming jaws, each having outwardly and inwardly inclined portions, the inclined portions of said jaws being arranged 20 to overlap in closed position on opposite sides of the neck of the bag, a pair of pivoted arms to which said jaws are fixed, an operating shifter and a pair of links connecting said shifter to said arms to open and close said jaws, substantially as described.

36. In bagging machines, the combination 25 with the bag-tying devices, of a pair of jaws, means for spreading and contracting said jaws, the latter being arranged to overlap in closed position to form the neck of the bag, a carrier reciprocating to and from said jaws, a series of catches on said carrier for holding the mouth of the bag and means for shifting said catches to closed 30 position as the carrier moves the upper portion of the bag into the path of the neck-forming jaws.

37. In bagging machines, the combination 35 with a hopper, of a circular series of catches 40 for holding the mouth of the bag below said hopper as it is filled, a pair of neck-forming jaws below said catches and each having outwardly and inwardly inclined portions, said inwardly inclined portions being arranged 45 to overlap in closed position on opposite sides of the neck of the bag, means for opening and closing said jaws, means for passing the cord around the neck of the bag formed by said jaws, cutters for severing 50 the separate lengths of cord and means for securing the ends of the cord together, substantially as described.

38. In bagging machines, the combination 55 with a hopper, of a circular series of radially movable catches for holding the mouth of the bag below said hopper as it is filled therefrom, means for shifting said catches apart and for shifting the same together to close the mouth of the bag, a pair of neck-forming jaws laterally movable below said 60 catches and each having an outwardly inclined portion and an inwardly inclined portion, the inclined portions of said jaws being arranged to overlap in closed position

on opposite sides of the neck of the bag, 65 mechanism for opening and closing said jaws, mechanism for passing the cord around the neck of the bag formed by said jaws and cutters for severing the separate lengths of cord and means for securing the 70 ends of cord together, substantially as described.

39. In bagging machines, the combination 75 with a hopper, of means for holding the neck of the bag below said hopper as it is filled therefrom, of a pair of neck-forming jaws having oppositely inclined portions arranged to overlap in closed position on opposite sides of the neck of the bag, a shifter arm for passing the cord around the neck of the bag formed by said jaws, said jaws and said shifter arm being arranged and operating in horizontal planes below said bag-holding means, mechanism for simultaneously operating said jaws and said shifter 80 arm, and mechanism for securing the ends of the cord together, substantially as described.

40. In bagging machines, the combination 85 with a hopper, of a circular series of radially shiftable catches for holding the 90 mouth of the bag below said hopper as it is filled therefrom, means for shifting said catches apart and for shifting the same together to close the mouth of the bag, a pair of neck-forming jaws having oppositely inclined portions arranged to overlap in closed 95 position on opposite sides of the neck of the bag, a shifter arm for passing the cord around the neck of the bag, said jaws and said shifter arm being arranged and operating in horizontal planes below said catches, common actuating means for said jaws and said shifter arm, cutters for severing the 100 separate lengths of cord and means for securing the ends of the cord together, substantially as described.

41. In bagging machines, the combination 105 with neck-forming jaws and means for opening and closing the same, of a pivoted, bent shifter arm for passing the cord around the neck of the bag formed by said jaws, said shifter arm having guides through which the cord extends, and actuating means for said shifter arm connected to and operated by one of said jaws, substantially as described.

42. In bagging machines, the combination 110 with a number of catches arranged in circular series for engaging the mouth of the bag, of means for shifting said catches to 115 close the mouth of the bag, a shifter-arm for passing the cord around the neck of the bag, cutters for severing the separate lengths of cord, means for securing the ends of the cord together, and mechanism for successively operating said catch-shifting means, said arm, 120 said cutters and said cord-securing means.

43. In bagging machines, the combination 125

with the series of shiftable catches for holding and closing the mouth of the bag and with the neck-forming devices, of a shifter for passing the cord around the neck of the bag, cutters for severing the separate lengths of cord, means for securing the ends of the cord together and a trip for releasing said catches.

44. In bagging machines, the combination 10 with a reciprocating carrier, of a number of catches thereon arranged in circular series, means for opening and closing said catches as the carrier is shifted, a shifter for passing the cord around the neck of the bag, cutters 15 for severing the separate lengths of cord and means for securing the ends of the bag together.

45. In bagging machines, the combination 20 with a reciprocating carrier, of a number of catches thereon arranged in circular series, means for opening and closing said catches as the carrier is shifted, neck-forming devices, a bent shifter-arm for passing the cord around the neck of the bag, cutters for severing 25 the separate lengths of cord and wire-cutting and twisting mechanism for winding the separate lengths of wire around the ends of the cord.

46. In bagging machines, the combination 30 with a reciprocating cord tightener, comprising a pair of bodily shiftable jaws, said jaws being movable together and apart in the direction transverse to the reciprocating movement of said tightener, a shifter arm 35 for passing the cord around the neck of the bag and through the jaws of said tightener, mechanism for successively shifting said arm and said cord tightener and means for opening and closing said jaws as said tightener is reciprocated, substantially as described.

47. In bagging machines, the combination 45 with a hopper, of means for holding the mouth of the bag below said hopper as it is filled therefrom, a pair of neck-forming jaws having oppositely inclined portions arranged to overlap in closed position on opposite sides of the neck of the bag, said jaws being movable in a horizontal plane below 50 said bag-holding means to and from closed position, a shifter arm movable in a horizontal plane with said jaws for passing the cord around the neck of the bag formed by said jaws, a horizontally movable cord 55 tightener having a pair of jaws movable therewith, means for opening and closing said tightener jaws as they are shifted, cutters for severing the separate lengths of the cord and means for securing the ends of the 60 cord together, substantially as described.

48. In bagging machines, the combination 125 of a shifter-arm for passing the cord around the neck of the bag, a spring-held dog on the end of said arm having an eyelet

through which the cord is threaded and a 65 movable cord-tightener having jaws through which the cord is passed by said shifter.

49. In bagging machines, the combination 70 with a shifter for passing the cord around the neck of the bag, of a spring-actuated cord-tightener and a catch for holding said tightener arranged to be released by the movement of said cord-shifter.

50. In bagging machines, the combination 75 with the bag closing devices, of a shiftable cord-tightener, a shifter arm for passing the cord around the neck of the bag and into the grip of said cord tightener, and means operated by the movement of said shifter arm for effecting the operation of said tightener, 80 substantially as described.

51. In bagging machines, the combination 85 with the neck-forming devices, of a shifter-arm for passing the cord around the neck of the bag, a pivoted spring-held dog on the end of said arm having an eyelet through which the cord is threaded, a shiftable cord-tightener having jaws through which the cord is passed by said shifter, means controlled by the movement of said shifter for 90 operating said tightener, cutters for severing the separate lengths of cord and means for securing the ends of the cord together.

52. In bagging machines, the combination 95 with the neck forming devices, of a pivoted shifter-arm for passing the cord around the neck of the bag, a spring-held dog pivoted on the outer end of said arm having an eyelet through which the cord is threaded, a movable spring-actuated cord-tightener having jaws through which the cord is passed by said shifter, a catch for holding said tightener arranged to be released by the movement of said cord-shifter and means for opening and closing said jaws as the tightener is shifted.

53. In bagging machines, the combination 100 with means for closing the mouth of the bag, of a clamp for holding the free end of the cord, a shiftable cord-tightener movable independently of said clamp, a shifter arm for passing the cord around the neck of the bag and into the grip of said cord tightener, means for severing the separate lengths of cord, means for securing the ends of the cord 110 together, and mechanism for successively operating said mouth-closing means, said shifter, said cord-tightener and said cord-severing and securing means, substantially as described.

54. In bagging machines, the combination 115 with means for closing the mouth of the bag, of a cord-tightener having jaws, a shifter for passing the cord around the neck of the bag and through the jaws of said cord-tightener, a clamp for holding the free end of the cord, cutters for severing the separate lengths of cord, means for securing the ends 125

of the cord together and means for releasing said clamp.

55. In bagging machines, the combination with means for closing the mouth of the 5 filled bag, of a normally stationary clamp for holding the free end of the cord, a cord-tightener having jaws, a shifter for passing the cord around the neck of the bag and through the jaws of said tightener, a cutter 10 independent of said cord-tightener for severing the separate lengths of cord, means for securing the ends of the cord together and means for releasing said clamp.

56. In bagging machines, the combination 15 with means for folding the mouth of the filled bag and with cutters for severing the separate lengths of cord, of a duplex clamp for gripping the free end of the cord, means for simultaneously passing the cord around 20 the folded part of the bag and through the open end of said clamp and means for operating said clamp to simultaneously release the cord and grip the new free end thereof, substantially as described.

25 57. In bagging machines, the combination with the cord-shifting mechanism, of an oscillating, duplex clamp for gripping the free end of the cord, a rotary spindle at right angles to the axis of oscillation of the clamp 30 whereon said clamp is mounted, and a stationary cam controlling the oscillating movement of said clamp as said spindle is rotated, substantially as described.

58. In bagging machines, the combination 35 with means for closing the mouth of the bag, of a shifter for passing the cord around the neck of the bag, cutters for severing the separate lengths of cord, an oscillating duplex clamp for gripping the free end of the cord, 40 said clamp being rotatable on the axis at right angles to its axis of oscillation, means for oscillating the clamp to release the cord and grip the new, free end thereof as said clamp is rotated, substantially as described.

45 59. In bagging machines, the combination with means for holding the mouth of the filled bag, of means for passing a cord around the folded part of the bag, a combined clamp and cutter and means for operating 50 the same to simultaneously sever the length of cord and to grip the new, free end thereof, substantially as described.

60. In bagging machines, the combination 55 of means for holding and folding the mouth of a filled bag, of a combined duplex clamp and cord cutter for normally gripping the free end of the cord, means for passing the cord around the folded part of 60 the bag and through the open end of said combined duplex clamp and cord-cutter, and means for operating said combined clamp and cord-cutter to sever the length of cord and grip the new, free end thereof, substantially as described.

61. In bagging machines, the combination with means for holding and folding the mouth of a filled bag, of a duplex clamp for gripping the free end of the cord, a cord tightener independent of said clamp, means for simultaneously passing the cord around 70 the neck of the bag through the open part of said duplex clamp and into the grip of said cord tightener, means for severing the separate lengths of cord and means for operating said duplex clamp to simultaneously 75 release the cord and grip the new, free end thereof, substantially as described.

62. In bagging machines, the combination with means for folding the mouth of a filled bag, of a normally stationary combined 80 duplex clamp and cord cutter, a cord-tightener independent of said clamp and cutter, a shifter for simultaneously passing the cord around the neck of the bag through the open end of said clamp and into the grip of said 85 cord-tightener, and means for operating said combined duplex clamp and cutter for simultaneously severing the length of cord and gripping the new free end thereof, substantially as described.

90 63. In bagging machines, the combination with means for folding the mouth of a filled bag, of a combined duplex cord clamp and cutter, a shifter movable in a horizontal plane for simultaneously passing the cord 95 around the folded part of the bag and through the open end of said combined clamp and cutter, and means for operating said combined clamp and cutter to simultaneously sever the length of cord and grip 100 the new free end thereof, substantially as described.

64. In bagging machines, the combination with the neck-forming devices, of a shifter for passing the cord around the neck of the 105 bag, a duplex rotatable combined cord clamp and cutter comprising two pairs of jaws and knives, means for rotating said combined clamp and cutter and a cam for alternately operating the jaws thereof as it is rotated, 110 substantially as described.

65. In bagging machines, the combination with the neck-forming devices, of a shifter for passing the cord around the neck of the bag, of a combined duplex rotary clamp and cutter for holding the free end of the cord and for severing the separate lengths thereof, means for imparting a one-half revolution to said combined clamp and cutter at each operation of the machine, and means 115 for oscillating said clamp and cutter as it is rotated.

66. In bagging machines, the combination with the neck-forming devices, of a shifter for passing the cord around the neck of the bag, a duplex, rotary, combined clamp and cutter for holding the free end of the cord and for severing the separate lengths there-

of, means for imparting a one-half revolution to said combined clamp and cutter at each operation of the machine and a fixed cam for operating said clamp and cutter as it is rotated.

67. In bagging machines, the combination with means for folding the mouth of a filled bag, of a shifter for passing a cord around the folded part of the bag, a combined clamp and cutter for gripping the free end of the cord and for severing the separate lengths thereof, a cord-tightener independent of said combined clamp and cutter, means controlled by said shifter for effecting the operation of said tightener and means for securing the ends of the cord together, substantially as described.

68. In bagging machines, the combination with means for folding the mouth of a filled bag, of a shifter for passing the cord around the folded part of the bag, a combined clamp and cutter for gripping the free end of the cord and for severing the separate lengths thereof, a cord-tightener independent of said combined clamp and cutter, means controlled by said shifter for effecting the operation of said cord-tightener, and a wire cutter and twister for severing the separate lengths of wire and twisting the same around the lengths of the cord, substantially as described.

69. In bagging machines, the combination with the slotted wire twister for winding wire around the ends of the cord, of means for passing the cord around the neck of the bag and the ends thereof through the slot of said twister and mechanism for operating said twister including a Geneva stop movement for accurately holding the slotted twister in position to receive the cord, substantially as described.

70. In bagging machines, the combination with the neck-forming devices, of a shifter for passing the cord around the neck of the bag, a rotary, slotted twister for winding wire around the ends of the cord, said shifter being arranged to pass around the end of said cord through the slot of said twister, mechanism for intermittently rotating said twister in one direction, and means for positively locking said twister against movement during the operation of said shifter, substantially as described.

71. In bagging machines, the combination with the neck-forming devices, of a rotatable slotted twister for winding wire around the ends of the cord, a shifter for passing the cord around the neck of the bag and the ends thereof through said slotted twister and mechanism for operating said rotatable twister including a Geneva stop movement for accurately holding the slotted twister in position to receive the cord, substantially as described.

72. In bagging machines, the combination with the machine frame and with means for folding the mouth of the filled bag, of a slotted, rotatable twister for winding wire around the ends of the cord, a clamp for holding the free end of the cord, a cord-tightener independent of said clamp, a shifter movable in a horizontal plane for simultaneously passing the cord around the neck of the bag through the slot of said twister, through said clamp and into the grip of said cord tightener, a cutter for severing the separate lengths of cord, and operating mechanism for said parts, substantially as described.

73. In bagging machines, the combination with the machine frame and with means for folding the mouth of a filled bag, of a slotted, rotatable twister journaled in the machine frame, an oscillating, rotatable duplex clamp for engaging the free end of the cord, a cord-tightener independent of said clamp, a shifter arm movable in a horizontal plane for simultaneously passing the cord around the folded part of the bag, through the slot of said twister, through the open end of said clamp and into the grip of said cord tightener, and a cutter for severing the separate lengths of cord, substantially as described.

74. In bagging machines, the combination with the machine frame and with means for folding the mouth of a filled bag, a slotted, rotatable twister for winding wire around the ends of the cord, a combined duplex cord clamp and cutter, and a horizontally movable shifter for passing the cord around the neck of the bag through the slot of said twister and through the open end of said combined cord clamp and cutter, substantially as described.

75. In bagging machines, the combination of the machine frame and with means for folding the mouth of the filled bag, of a slotted, rotatable twister for winding wire around the ends of the cord, a combined duplex cord clamp and cutter, a cord-tightener, a shifter for simultaneously passing the cord around the folded part of the bag through the slot of said twister, through the open end of said duplex clamp and cutter and into the grip of said cord-tightener, and operating mechanism for said parts, substantially as described.

76. In bagging machines, the combination with the neck-forming devices, of a slotted rotatable twister for winding wire around the ends of the cord, a shifter for passing the cord around the neck of the bag and the ends thereof through the slot of said twister, a combined rotary cord clamp and cutter and a cord-tightener controlled by the operation of said shifter.

77. In bagging machines, the combination

with the cord-shifting mechanism, of a twister for winding wire around the ends of the cord, said twister comprising two, rotatable, relatively movable parts arranged 5 to grip the free end of the wire between them, substantially as described.

78. In bagging machines, the combination with means for folding the mouth of a filled bag, of means for passing the cord around 10 the folded part of the bag, and a rotatable twister for winding wire around the ends of the cord, having a movable part thereon for engaging and securely gripping the free end of the wire.

79. In bagging machines, the combination 15 with the means for folding the mouth of the filled bag, of means for passing the cord around the folded part of the bag, and a slotted, rotatable twister through which the 20 ends of the cord are passed for winding wire around the ends of the cord, said twister having a relatively movable grip member thereon for securely engaging the free end of the wire.

80. In bagging machines, the combination 25 with the cord carrying mechanism, of a twister for winding wire around the ends of the cord comprising two rotatable members between which the free end of the 30 wire is gripped, said members having a lost motion connection between them.

81. In bagging machines, the combination 35 with the cord carrying mechanism, of a twister for winding wire around the ends of the cord comprising two rotatable members between which the free ends of the wire is gripped, said members having a lost motion connection between them, means for positively driving one of said members and 40 means for initially retarding the movement of the other of said members.

82. In bagging machines, the combination 45 with the cord carrying mechanism, of a twister for winding wire around the ends of the cord comprising two rotatable members having slots through which the cord is passed, means on said members for grip-

ping the free end of the wire, means for positively driving one of said members, and means for initially retarding the movement 50 of the other of said members.

83. In bagging machines, the combination with the cord carrying mechanism, of a twister for winding wire around the ends of the cord comprising two rotatable members 55 having slots through which the cord is passed, means on said members for gripping the free end of the wire, means for positively driving one of said members, including the Geneva stop movement and 60 means for positioning and initially retarding the movement of the other of said members.

84. In bagging machines, the combination 65 with the cord carrying mechanism, of a combined rotary twister and cutter for severing the separate lengths of wire and winding them about the ends of the cord, comprising two rotary members having devices 70 for gripping the free end of the wire and 75 slots extending to the center of said rotary members through which the ends of the cord are passed, one of said members having a knife edge at its periphery for severing the separate lengths of wire and means for 75 feeding and guiding the wire to said twister and cutter.

85. In bagging machines, the combination 80 with the cord carrying mechanism for passing the cord around the neck of the bag, of a wire twisting device for winding wire around the ends of the cord, comprising a pair of rotary members having slots extending 85 to the center thereof through which the ends of the cord are passed, an eccentric grip finger for engaging the free end of the wire on one of said members extending through a slot in the other of said members and means for positively driving one of said members.
